(57) **CLAIM**

The ornamental design for an elongated shoe horn with clip, as shown and described.

DESCRIPTION

FIG. 1 is a front view of the elongated shoe horn with clip showing our new design;

FIG. 2 is a side view thereof;

FIG. 3 is a rear view thereof;

FIG. 4 is a rear perspective view thereof; and,

FIG. 5 is an enlarged end view thereof.

The broken lines shown in the drawings are for illustrative purposes only and form no part of the claimed design.
